UNITED STATES PATENT OFFICE.

WILLIAM H. ALBEE, OF MARLBORO, MASSACHUSETTS, ASSIGNOR TO KOEHLER MANUFACTURING COMPANY, OF MARLBORO, MASSACHUSETTS, A CORPORATION OF MASSACHUSETTS.

PROCESS OF MAKING FOOTBALL CLEATS.

Original application filed October 21, 1926, Serial No. 143,206. Divided and this application filed March 26, 1927. Serial No. 178,732.

This invention relates to football cleats and to processes of manufacturing them.

The usual process heretofore practiced of equipping a shoe with a football cleat has consisted in cementing together pieces of leather to build up a block or blank of the desired height, then nailing this assembled piece to the bottom of a shoe, and finally trimming said piece either with a knife or with a hammer and chisel to form a cleat of the desired shape and size. This process obviously requires a great deal of hand labor, it produces cleats which are not uniform in size or shape, and there is great danger of cutting the sole or heel of a shoe in trimming the cleat. In fact, this process really involves performing the greater part of the manufacturing operations on the cleat after it has been secured to the shoe.

20 The present invention aims to improve this process with a view to reducing the expense involved, improving the quality of the work produced, substantially eliminating the danger of injuring the shoe, and producing a superior cleat.

The nature of the invention will be readily understood from the following description when read in connection with the accompanying drawings, and the novel features will be particularly pointed out in the appended claims.

Referring now to the drawings,

Figure 1 is a perspective view of a cleat blank or block;

35 Fig. 2 is a perspective view of the block after it has been trimmed;

Fig. 3 is a perspective view of a completed cleat;

40 Fig. 4 is a transverse, vertical, cross-sectional view of the cleat shown in Fig. 3;

Fig. 5 is a cross-sectional view showing the manner in which the cleat preferably is secured to the sole of a shoe;

45 Fig. 6 is a plan view of another form of cleat embodying this invention;

Fig. 7 is a perspective view of the cleat shown in Fig. 6; and

50 Fig. 8 and 9 are side views of portions of mechanisms which may conveniently be used in performing certain of the cleat trimming operations.

According to the present process the manufacturing operations on the cleat are first

completed and subsequently it is secured to the bottom of a shoe.

The cleat may be made of any suitable material but usually it consists of several lifts of leather 2 cemented together, one on top of the other, to form a blank of the desired dimensions. This blank is then run through 60 or between cutters which trim its edges or sides, producing the inclined edge faces which give it the shape of a frustum of a pyramid, as shown in Fig. 2. The cleat is next molded or compressed in suitable dies 65 or molds for the purpose of consolidating the stock, and of concaving the bottom of the cleat, as indicated at 3 in Figs. 3 and 4. That is, the bottom is inwardly curved, being given substantially the shape of the surface 70 of a section of a cylinder, the axis of which extends lengthwise of the cleat, so that the two edges at opposite sides of the base of the cleat lie below the remainder of the base. This makes the base of the cleat conform 75 substantially to the curvature of the sole of a shoe so that when it is nailed on the sole the edges of the cleat will hug the sole tightly. The concave shape of the base also has the advantage of preventing the edges of the 80 cleat from curling up when the cleat is nailed to the shoe, which has been an objectionable feature of prior constructions.

During the molding operation and while the surfaces of the cleat are confined against 85 distortion, several holes, usually four, are punched almost through the cleat from the upper surface thereof, these holes being designed to receive the nails or other fastenings by means of which the cleat ultimately will 90 be secured on the bottom of the shoe. The cleat in this condition forms an article of commerce. I prefer, however, before marketing the cleat, to drive into it the fastenings by means of which it is to be secured to the shoe, thus producing a cleat 95 that is entirely self-contained. A particular advantage of this arrangement is that the nails can all be driven at once by machinery so that a substantial saving in labor is effected, the nails are driven uniformly, and the attaching of the cleat to the shoe is facilitated. The punching of the holes practically through the cleat avoids the danger which otherwise would be present of the nails being 100 diverted during the driving process, with 105

the consequent damage to the cleat and probably also to the shoe. Figs. 3 and 4 show the cleat C with nails 4 partially driven therethrough, the head and a substantial length of each nail projecting above the upper surface of the cleat. These nails preferably are driven into the position shown in Figs. 3 and 4 while the base of the cleat rests on a curved support so that the curvature of the bottom of the cleat will not be distorted. The points of the nails may prick through the bottom face of the cleat.

10 The entire trimming operation need not precede the molding; in fact it is preferable under some circumstances to trim the block longitudinally to produce the opposite inclined edge or side faces, then compress it, and subsequently, while the block is in the more consolidated and stable condition, to trim the remaining pair of edges or end faces. The holes are punched later while the cleat is supported against distortion.

15 For the purpose of affixing a cleat to the bottom of a shoe an iron last usually is inserted within the shoe. The cleat C is placed in the desired position on the shoe bottom, and the nails 4 are then driven through the cleat and into the shoe sole, the points 5 of the nails clenching on the surface of the iron 20 last. There is considerable danger of splitting the cleat during this operation, or at least distorting it so much that it presents an unsightly appearance, and in order to overcome this objection I prefer to confine 25 the lateral faces or edges of the cleat while the fastenings are being driven. For this purpose the cleat preferably is attached by means of a tool like, or similar to, that shown 30 in my Patent No. 1,568,308, dated January 5, 1926, this tool having a cavity to receive the cleat and support its lateral edges while the 35 fastenings are being driven.

40 Fig. 5 shows the cleat in cross-section after it has been secured to the bottom of the sole 45 of a shoe S, the end 5 of the nail 4 being clenched, as clearly illustrated. By shaping the cleat, as above described, and supporting its faces against distortion during the operations of punching holes therein and driving 50 fastenings therethrough, any danger of splitting the cleat, or distorting it substantially 55 is completely avoided. Consequently, when the process has been completed, the cleat presents a neat and finished appearance. Furthermore, this invention not only results in 60 giving the cleats a uniform and more satisfactory appearance, but it applies them to the shoe in such a manner that they are stronger and there is substantially less 65 danger of their becoming loosened than when applied by the processes heretofore practiced. In attaching prior cleats there has been considerable tendency for the edges to curl up and thus provide a crease between 70 the cleat and the face of the sole into which

dirt and mud would work. This crease also facilitates the loosening of the cleat. The construction above described, however, effectively prevents such an occurrence, the longitudinal edges of the cleat at the base hugging the sole tightly. Any danger of cutting the shoe is completely avoided, and damage to the shoe or the cleats due to improper driving of the fastenings is eliminated. Furthermore, the cleats provided by this invention are preferred by the trade because they can be applied to the shoe more easily, particularly when they are loaded 75 with nails, as above described.

80 It is a common practice to secure a considerable number of these cleats, frequently seven, on the sole of a shoe, and usually three are nailed to the heel of a football shoe. In playing on a muddy field it is found that the mud packs badly between the cleats so that 85 much of their usefulness is lost. I have found that this difficulty can be reduced very substantially by making the cleats in the form shown at D in Figs. 7 and 8. These 90 cleats are made from a blank like that shown in Fig. 1, the longitudinal edges being trimmed by forcing the blank between stationary inclined knives set at the proper angle to produce the inclined lateral edge 95 faces, as above described in connection with Figs. 1 and 2. The cleat in this condition is then trimmed to produce rounded or convex inclined ends, as shown at 6-6 in Figs. 6 and 7. This trimming operation may 100 conveniently be performed in the machine shown in another application, certain features of this machine being shown in Fig. 8.

105 Referring to the latter figure it will be observed that the machine includes a holder 7 provided with a cavity 8 in which the partially trimmed cleat is inserted. Preferably the cleat has been molded before this end trimming operation is performed, and the holder serves to prevent any substantial distortion of the cleat during this operation, the 110 holder having surfaces to engage the inclined edges and the concave bottom of the cleat. A spring pressed plunger 9 holds the cleat compressed and firmly secured in the holder 7, while knives 10-10, carried by a rotary head 12 which is mounted to rise and fall, shave or trim the surplus stock off the ends of the cleat. The holder 7 preferably is 115 stationary while the knives rotate about it, these knives revolving about an axis extending vertically and centrally through the cleat D. As the cutter head 12 is lowered the knives trim off substantially all the material projecting beyond the edges of the holder 120 and produce the convex end surfaces 6-6, as shown in Figs. 6 and 7. Substantially the same organization can also be used in trimming frusto-conical cleats, as shown in Fig. 9, the cleat blank being supported on 125 a post or holder 7', while the knives 10'-10' 130

carried in the rotating and rising and falling head 12' trim the blank down to the desired size and shape.

The cleats shown in Figs. 6 and 7 preferably have holes punched in them in the manner above described in connection with the cleat shown in Figs. 3 and 4, and they are loaded with nails in the same way, care being taken to prevent them from being split or distorted while the holes are being punched and the nails driven.

These round ended cleats do not present the same opportunity for the packing of mud between adjacent cleats as do the cleats shown in Fig. 3. That is, they do not present broad flat surfaces in opposed contiguous relationship to each other where the mud can wedge in between them. At the same time they have the strength and ground gripping properties of the cleat shown in Fig. 3.

This application is a division of my pending application Serial No. 143,206, filed October 21, 1926.

Having thus described my invention, what I desire to claim as new is:

1. That improvement in the process of manufacturing football cleats which consists in cementing together lifts of leather, one upon the other, to form a cleat blank of approximately rectangular form, trimming opposite edges of said blank to produce inclined edge faces thereon and to make the top of the blank much smaller in area than the bottom, and trimming the opposite ends of the blank to produce inclined convex end faces thereon.

2. That improvement in the process of manufacturing football cleats which consists in cementing together lifts of leather, one upon the other, to form a cleat blank of approximately rectangular form, trimming the edges of said blank to produce inclined edge faces thereon and to make the top of the blank much smaller in area than the bottom, and molding the cleat so formed to concave the bottom thereof.

3. That improvement in the process of manufacturing football cleats which consists in cementing together lifts of leather, one upon the other, to form a cleat blank of approximately rectangular form, trimming opposite edges of said blank to produce inclined edge faces thereon and to make the top of the blank much smaller in area than the bottom, trimming the remaining pair of edges to produce inclined edge faces thereon, molding said cleat to concave the bottom

thereof so that the longitudinal edges of the base of the cleat will lie in a different plane from the center line of said base, making holes in the cleat to receive fastenings by which it is to be secured to a shoe, and supporting the cleat against distortion while said holes are being made.

4. That improvement in the process of manufacturing football cleats which consists in cementing together lifts of leather, one upon the other, to form a cleat blank of approximately rectangular form, trimming opposite edges of said blank simultaneously to produce inclined edge faces thereon and to make the top of the blank much smaller in area than the bottom, and shaping the opposite ends of the blank to produce inclined rounded end faces thereon.

5. That improvement in the process of manufacturing football cleats which consists in cementing together lifts of leather, one upon the other, to form a cleat blank of approximately rectangular form, trimming opposite edges of said blank to produce inclined edge faces thereon and to make the top of the blank much smaller in area than the bottom, trimming the remaining pair of edges to produce inclined edge faces thereon, and supporting the cleat against distortion while the latter pair of edges is trimmed.

6. That improvement in the process of manufacturing football cleats which consists in cementing together lifts of leather, one upon the other, to form a cleat blank, trimming the edges of said blank to produce inclined edge faces thereon and to make the top of the blank much smaller in area than the bottom, molding and pressing the cleat, making holes in the cleat to receive fastenings by which it is to be secured to a shoe, and supporting the cleat against distortion while said holes are being made.

7. That improvement in the process of manufacturing football cleats which consists in cementing together lifts of leather, one upon the other, to form a cleat blank of approximately rectangular form, trimming opposite edges of said blank to produce inclined edge faces thereon and to make the top of the blank much smaller in area than the bottom, shaping the opposite ends of the blank to produce convex end faces thereon, and compressing the blank while said shaping operation is being performed.

In testimony whereof I have hereunto signed this specification.

WILLIAM H. ALBEE.
